ABSTRACT OF THE DISCLOSURE

A speech synthesizer for compiling a speech from pre-recorded acoustic elements, wherein said acoustic elements are classified into two groups, one being a number of damped sinusoidal waves of different frequencies from which vowels and transient sounds of speech are produced according to control signals, the other being continuous signals having features of respective consonants, and the speech being synthesized by combining selected ones of said vowels and transient sounds with selected ones of said continuous signals corresponding to consonants.

This invention relates to a speech synthesizer, particularly to a system for artificially reproducing speech by compiling pre-recorded acoustic elements (hereafter referred to as a pre-record and compilation system).

In a pre-record and compilation system, as a pre-recorded unit is usually employed a word. Therefore, in order to increase the amount of speech synthesizable and to expand its application range from a limited particular field to a more generalized scope, a drastic increase in the number of units of speech (or words) to be pre-recorded is required. Such increase of the pre-recorded words inevitably invites bulkiness and complication of the system and further, increases the access time required for reading out wanted words.

One approach for solving the above problem may be to store, as pre-recorded units or the acoustic elements, mono-syllables instead of words. With this method, however, it is known that the quality of the compiled speech is poor both in clearness and in naturalness. A reason for this inferior quality of the thus synthesized speech will be that a word made by combination of syllables is very different in the characteristic features of the component syllables such as the frequencies of formants, the intensity of envelope, the frequency of pitch, and the duration, from the naturally pronounced same word in an integral speech uttered with a particular meaning. To solve this problem, the only way is to increase the number of the pre-recorded units or acoustic elements, which contradicts the purpose for which syllables are adopted as the elements to be stored.

The main object of this invention is to provide an improved speech synthesizer of the pre-record and compilation system in which the above defects have been removed. Namely, the objects of this invention are to increase the variety of the synthesizable speech, to minimize the number of the acoustic elements to be stored as basic units or constituents of synthesized speech, to improve the quality of the synthesized speech, especially

2

in the naturalness of the speech, and to reduce the size of the system.

According to this invention, as an acoustic element to be stored, voiced sounds each having a constant repetition rate and consonants including nasal consonants, unvoiced consonants and voiced consonants are employed. Each voiced sound is produced by selectively reading out and compiling together, at varied intervals determined by a control signal, a number of damped sinusoids of different frequencies which have been prerecorded on a recording medium. On the other hand, the consonant part is compiled of a number of naturally pronounced consonants or synthesized consonants which represent the characteristic features of the natural consonants. These constituent consonants are pre-recorded in a recording medium, and read out under control of a control signal with the timing of the read-out and the duration being controlled.

This invention will be described in detail with reference to the accompanying drawings, in which

FIGS. 1a, 1b and 1c show a waveform of speech and the spectrum characteristics thereof;

FIGS. 2a, 2b, 2c and 2d show a waveform of a particular oscillation and the spectrum characteristics thereof;

FIGS. 3 and 4 are schematic diagrams illustrating the synthesis of waveforms by means of a magnetic drum;

FIG. 5 is a block diagram of an embodiment of a speech synthesizer according to this invention; and

FIGS. 6 and 7 are diagrams for explaining the operation of the essential portions of the above embodiments.

Fundamentally, a voice is produced when either of a voiced sound caused by the vibration of vocal chords which is almost periodically repeated intermittent triangular waves or an unvoiced sound caused by a turbulent flow produced by contract of the vocal tract which is almost white random noise is passed through a cavity formed in the vocal tract, that is, an articulatory organ formed from the glottis to the lips. In FIG. 1a which shows a part of a waveform of a speech, the section indicated by reference numeral 1 represents a voiced sound in which the repetition rate of a vocal base is constant, and the section 2 a consonant. The frequency spectrums of the above sounds 1 and 2 are characterized, as shown in FIGS. 1b and 1c respectively, by spectrum envelopes 3 which are indications of resonant characteristics of the articulator and by the inner structure of the spectrum indicating the features of the vocal base, the former being further characterized mainly by several single-resonance characteristics (that is, formants) 4, 4', 4'', 5, 5' and the latter being characterized mainly by a harmonic line spectrum 6, which possesses periodicity and randomness of continuous spectrum.

According to this invention, it facilitates to synthesize a voiced sound of a constant repetition rate, for example, having a characteristic spectrum as shown in FIG. 1b from a number of pre-recorded damped sinusoidal waves of different frequencies. The principle of this synthesis will be explained hereunder.

A damped sinusoidal oscillation as shown in FIG. 2a gives a single-resonant frequency spectrum as shown in FIG. 2b, said damped sinusoidal oscillation being represented by the formula $e^{-\alpha t} \sin \omega_i t$, where α is the damping factor, t the time, and ω_i the angular frequency of the oscillation. If the damped sinusoidal oscillations are re-

peated at a constant period T as shown in FIG. 2c, the frequency spectrum thereof will become a harmonic line spectrum as shown in FIG. 2d. It is known in the acoustical theory on production of voice that the spectrum envelope 3 as shown in FIG. 1b is produced by continuously cascading the single-resonant features as shown in FIG. 2b. Therefore, such a voiced sound as the period of pitch or the repetition period of the vocal base is constant, for example, vowel "O", can be synthesized by repeatedly reproducing, at a predetermined period, a recorded damped sinusoidal wave having the formant frequency equivalent to that of the vowel in such a manner that the amplitudes of the reproduced oscillation waves are controlled according to the following conditions;

the relative amplitude of the second formant is $(\omega_1/\omega_2)^2$,
the relative amplitude of the third formant is $(\omega_1/\omega_2)^2(\omega_2/\omega_3)^2$;

where ω_1 , ω_2 and ω_3 indicate respectively an angular frequency of the first, the second and the third formants of the voice.

Further, a transient sound from a voiced sound of a constant repetition rate, that is, a sound having a particular frequency spectrum, to another sound having another frequency spectrum, can be synthesized, with sufficient smoothness, according to the following steps; that is, quantizing a variation in frequencies of the characteristic formants of the respective sounds between said two voices; synthesizing sounds by adding the damped sinusoidal oscillations as described above; and then joining the sounds consecutively.

Accordingly, in the speech synthesizer of this invention, the number of the acoustical elements to be pre-recorded is required only to be enough to cover, with an appropriate space, the frequency bands which are essential for constituting a speech (including as far as the first, the second and the third formants). An example of such a number as realized in an embodiment of this invention is shown in the following Table 1.

TABLE 1.—AN EXAMPLE OF THE NUMBER OF THE RECORDED ACOUSTICAL ELEMENTS OF DAMPED SINUSOIDAL OSCILLATION

Formant	Frequency range, Hz.	Quantizing increment	Number of channels	Number of bits
First	200-950	50 Hz	16	4
Second	800-2,400	Logarithmic scale	16	4
Third	2,200-3,500	do	8	3
Total	200-3,500		40	11

As to the consonant portions of the voice (nasal consonant, unvoiced consonant and vocal or voiced consonant), it is only required to pre-record signals corresponding to the features of respective consonants. The number of such signals is at most 16 as shown in the following Table 2.

TABLE 2.—AN EXAMPLE OF THE NUMBER OF CONSONANTAL ELEMENTS TO BE RECORDED

Fricative sounds		Plosive sounds		Nasal sounds	
Consonants	Number of elements	Consonants	Number of elements	Consonants	Number of elements
s	1	p	1	m	1
f	1	t	2	n	1
h	5	k	3	N	1

Therefore, the total number of the acoustical elements to be recorded will be of the order of fifty. In order to improve the naturalness of the thus compiled speech, it is required to control the period of the above-described repetitive reproduction of the damped sinusoidal oscillations in accordance with the pitch period of the speech to be synthesized. A tangible method of such a control will be described hereunder with reference to FIG. 3 which

illustrates schematically a magnetic drum on which the above-mentioned damped sinusoidal oscillations are recorded.

Assuming that the lowest frequency of the pitch of the speech to be synthesized is 50 Hz., the damped sinusoidal oscillations are recorded for 20 ms. which corresponds to one revolution period of the drum. (This means that the time constant of damping is assumed to be about 20 ms. at most. This assumption will be appropriate in view of the band width of vowel formants.) For example, ten read-out heads are disposed at an equal space along the circumference of the drum, the time difference between two adjacent heads will be 2 ms. This is the minimum controllable step of the pitch period, and the pitch frequency is controlled according to the selection of read-out with the following ten steps: 50 Hz., 55.5 Hz., 62.5 Hz., 715 Hz., 83.5 Hz., 100 Hz., 125 Hz., 166 Hz., 250 Hz. and 500 Hz. It will be understood that these steps can be shortened by increasing the number N of the heads.

Referring to FIG. 3, it is assumed that the I_0 -th head is reading at an instant and that T_0 is the time interval between the reading with the I_0 -th head and with I_1 -th head. If the next reading is started when the beginning 25 of the recorded signal comes to the position of the (I_1+k) -th head, the interval between two readings will become longer by τk seconds. While, if it is started at the position of the (I_1-k) -th head, the interval will become shorter by τk seconds. (τ indicates the time that the rotating drum takes to move from a head to the next head.) Assuming that the recorded signal is read out by a head continuously for one revolution of the magnetic drum, that is, for 20 ms., it will be seen from FIG. 4 that the beginning portion of a reading period overlaps a portion of the signal read by the preceding acting head and the ending portion overlaps with a portion of the signal read by the ensuing head, thus the transition of physical features is achieved more smoothly, resulting in an improved quality of the synthesized speech.

In the following paragraphs, the pre-record and compilation type speech synthesizer of this invention will be described in detail in connection with an embodiment of the invention.

In FIG. 5 which is a block diagram of an embodiment 45 of this invention, a multiple output system of n channels is shown. Constituents of the sentence to be converted to a speech, which are selected in the main apparatus 10 of the information processing system (usually, a common large high-speed electronic computer), are immediately converted into speech output control signals 11, 12, . . . 1 n , with reference to a magnetic drum 20 which contains a pronounce dictionary (a stock of control signals for speech units to be articulated), and then are distributed to control signal decoders 101, 102, . . . 10 n 50 for the respective channels where the distributed control signals are decoded to a group of more tangible control

signals 21, 22, . . . 2 n for reading the recorded acoustical elements. A part of the decoded signals is led to the recorded elements selecting gate matrixes 201, 202, . . . 20 n , while the remaining part is led to groups of controlling analogue multipliers (311, 312, 313), (321, 322, 333) . . . (3 n 1, 3 n 2, . . . 3 n 3) for controlling the relative amplitudes of the readout signals. Thus, a specified acoustical element is read out through a specified

head on the elements storage drum 30 at a specified time; and then the relative amplitude is controlled as required. The amplitude controlled outputs are led to summing amplifiers 314, 324, . . . 3n4 in the respective channels and are added to each other, and then are controlled in regard to the intensity in multipliers 315, 325, . . . 3n5 as required for a phoneme and integral speech. After that, the outputs are combined with consonants in summing amplifiers 316, 326, . . . 3n6 to become the resultant vocal outputs 31, 32, . . . 3n. The above-described process is repeated, for example, every 10 ms., thereby to produce a continuous speech output.

Next, the essential components of the system will be described in more detail. As has been explained already, according of this invention, a voice is separated into two parts, that is: (1) vowels and transient sounds (including semivowel and fluent sound) and (2) consonants (unvoiced consonants, voiced consonants and nasal consonants). In synthesizing speech, the part (1) is produced by reading out repeatedly but in varied periods the recorded damped sinusoidal waveforms, and the part (2) by directly reading out the required waveforms out of the recorded consonantal ones, and finally both parts are combined. It is known already that the fricative sounds and plosive sounds can be produced by increasing the overlap of the consonant part (2) and the vowel and transient part, and the plosive sounds also by making steep the vowel and transient part. Therefore, any syllable can be synthesized from the above-described parts (1) and (2).

Of the parts (1) and (2), only the part (1) is necessary to be repeatedly read out at varied periods, and the variable periods are common to all of the first, second and third formants.

Therefore, the read-out of the recorded acoustical elements will be explained hereunder relating to a particular channel. The acoustical elements recorded on the magnetic drum are classified into two categories, that is: a group of damped sinusoidal waves used for the synthesis of the above-described part (1) and a group of consonantal waves. The first group is divided into three ranges overlapping each other in the fringe portions, that is: the first formant range (16 channels from 200 to 950 Hz.), the second formant range (16 channels from 800 to 2,400 Hz.) and the third formant range (8 channels from 2,200 to 3,500 Hz.). In order to simplify the structure for control, channels on the magnetic drum are divided corresponding to the above two categories, the first category being further divided into three zones, namely, the first, second and third zones. Thus, the recording channels of the drum are divided into four zones. That is, as shown in FIG. 6, the elements storage drum 400 is divided into four zones 401, 402, 403 and 404. Outputs of reading heads for respective channels in said four zones are led to the gate matrixes 411, 412, 413 and 414 for selecting outputs. Of said four gate matrixes, the matrixes 411, 412 and 413 for composing the formants are supplied commonly with a head selecting signal 451, while the remaining matrix 414 is supplied with a signal 452 for selecting the consonant reading head.

In order to determine which channel (frequency) should be selected in the respective zones, frequency selecting signals 461, 462 and 463 are given to the respective matrixes as the first, second and third formants should be independently controlled. According to these control signals, damped sinusoidal waves of different frequencies (corresponding to the formant frequencies) repeatedly read out at particular periods (corresponding to the pitch periods) are obtained at output terminals 471, 472 and 473 of the gate matrixes 411, 412 and 413. The outputs from matrixes 412 and 413 are controlled as to the relative amplitudes to the output from the matrix 411 in analogue multipliers 422 and 423 with reference to control signals 465 and 466, and then added to the latter output in a summing amplifier 431. Output from the summing amplifier 431 is further controlled as

to the amplitude in an analogue multiplier 441 with reference to a control signal 481 so as to give a good effect of vocal sound and speech, and then let out through an output terminal 490 as a continuous speech.

If a consonant is required, the consonant selected by the matrix 414 is added to the vowel and transient sound in a summing amplifier 440, after the consonant is imparted an appropriate control of the amplitude relative to the vowel and transient sound in an analogue multiplier 424 and with reference to the control signal 468.

FIG. 7 shows in more detail a part of one of the recorded elements selecting gate matrixes 411, 412, 413 and 414 shown in FIG. 6. As the gate matrixes 411, 412, 413 and 414 are substantially the same in operation, the following description will be made as to only one of them.

In FIG. 7, it is assumed that l recorded channels 1, 2 . . . l on the magnetic drum are to be selectively read-out by N reading heads 1, 2 . . . N .

Signal 451 (for the matrixes 411, 412 and 413) or signal 452 (for the matrix 414) which specifies the heads by which the recorded signals are to be read out, is led to a decoding buffer 500 to be decoded therein. The decoding buffer 500 supplies output "1" to output lines 20 leading to the specified heads and output "0" to all of the remaining lines out of the lines 501 to 50N.

Meanwhile, signal 461 (for 411), signal 462 (for 412) or signal 463 (for 413) which specifies the channels of which the outputs are to be taken, is led to another decoding buffer 600 to be decoded therein. The decoding buffer 600 supplies signal "1" to the selected lines and signal "0" to the remaining lines out of the lines 601, 602 . . . 60l. As to the analogue read-out from each channel on the magnetic drum, outputs from the channels associated with the 1st heads are connected to terminals 11, 12 . . . 1l respectively, outputs from the channels associated with the 2nd heads are connected to terminals 21, 22 . . . 2l, and outputs from the channels associated with the N -th heads are connected to terminals 40 N1, N2 . . . Nl respectively.

Gate selecting signals 501, 502 . . . 50N and 601, 602 . . . 60l are first connected to selecting digital AND gates 111, 121 . . . 1l; 211, 221 . . . 2l; and N11, N21 . . . Nl respectively, as shown in the figure. As the result, among the $N \times l$ gates only one gate, which receives the specified signal "1", opens to give an output "1" to the associated gate among the ensuing analogue gates 112, 122 . . . 1l; 212, 222 . . . 2l; N12, N22 . . . Nl. Thus, the output of the specified head read from the specified channel is selected.

Further, the decoded output from the decoding amplifier 500 specifies not only the head to be selected, but the time at which the signal is read out from the head. (As the signal is always read out from the starting point of the record, the starting time can be easily determined from the timing pulse on the drum.) Therefore, assuming that the digital AND gates 111, 112 . . . N11, if they are opened once, maintain the output "1" during a complete revolution of the drum (the period being T_0 ms., for example, 20 ms.), then this selecting gate matrix allows a read-out as shown in FIG. 4.

The read-out outputs are summed and let out from the output amplifier 700. This output corresponds to either one of the outputs 471, 472 or 473 in FIG. 6.

In the consonant selecting gate matrix, the read-out of a specified head from a specified channel is required to continue during the duration inherent to the particular consonant. It is achieved by controlling the duration with the decoded signal from the decoding buffer 500, whereas the duration is constant (for example, 20 ms.) in the case of vowels. This output corresponds to 474 in FIG. 6.

It will be obvious that the above-described principle of this invention is equally applied either to a digital type recording of the acoustic elements or a cyclic memory consisting of a group of shift registers. However, it will

be understood that in a digital recording, a digital-to-analogue converter is required for converting the read-out output to an analogue waveform.

What we claim is:

1. A speech synthesizer of the pre-record and compilation type comprising: a memory on which a number of damped sinusoidal waves of different frequencies are recorded; means for selectively reading out at least one of said sinusoidal waves periodically according to a control signal, said period of reading out being variable; a memory on which a number of continuous signals having features of respective consonants are recorded; and means for selectively reading out at least one of said continuous signals at a specified time according to a control signal.

2. A speech synthesizer according to claim 1, which

further comprises means for compiling the outputs of the first and second mentioned reading out means together.
